H. B. PALMER

APPARATUS FOR ADMINISTERING RADIUM EMANATIONS

Filed Nov. 16, 1923

UNITED STATES PATENT OFFICE.

HARRY B. PALMER, OF MENDHAM, NEW JERSEY.

APPARATUS FOR ADMINISTERING RADIUM EMANATIONS.

Application filed November 16, 1923. Serial No. 675,119.

This invention relates, generally, to a novel means of supplying and a novel means for administering to patients medicinal doses of radium emanation.

5 The invention has for its principal object to provide a novel sealed capsule or cartridge charged with radium emanation or gas, the content of which, by means of a novel apparatus, may be administered in 10 predetermined dosage quantity to the user or patient; and the invention also has for a further object to provide a novel construction of device adapted to both measure and administer to the patient a predetermined 15 quantity of the radium emanation content of a capsule or cartridge according to the desired dosage without danger of loss or deterioration.

Other objects of this invention, not at 20 this time more particularly enumerated, will be clearly understood from the following detailed description of the same.

With the various objects of this invention in view, the same consists, primarily, in the 25 novel means for dispensing and administering medicinal doses of radium emanation hereinafter set forth; and the invention consists, furthermore, in the novel arrangements and combinations of the several devices and parts comprising the dose administering apparatus, as well as in the details 30 of the construction of the same, all of which will be more fully described in the following specification, and then finally embodied 35 in the claims appended thereto.

The invention is clearly illustrated in the accompanying drawings, in which:—

Fig. 1 shows a vertical longitudinal section of the novel apparatus for administering medicinal doses of radium emanation, the same being charged with a radium emanation containing capsule or cartridge disposed in normal initial position ready for use; Fig. 2 is a side view of the capsule or cartridge holder of the apparatus, the same being removed from operative relation to the main body of said apparatus; Figs. 3 and 4 are fragmentary vertical longitudinal sections of the apparatus, showing different stages of the operations for removing

successive doses of radium emanation from the containing capsule or cartridge; Fig. 5 is a detail transverse section, taken on line 5—5 in Fig. 3 looking upward; and Fig. 6 is an enlarged fragmentary vertical longitudinal section, showing the operation of the means for tapping or discharging the content of the capsule or cartridge.

Similar characters of reference are employed in all of the hereinabove described views, to indicate corresponding parts.

Referring now to said drawings, the reference character 1 indicates a bottle-like container or jar which provides a water reservoir or chamber 2, the same having an open filling neck or mouth at its upper end. Removably connected with said container or jar 1, by fitting its depending stopper-boss into said filling neck or mouth 3, is a housing member 5 having an interior chamber 6 open at its lower end so as to communicate with the water reservoir or chamber 2 of the container or jar 1. The upper end of said housing member 5 terminates in a tubular neck-portion 7 of reduced diameter, providing a passage 8 which is open at its upper end, and which communicates at its lower end with the interior chamber 6 of said housing member. Formed in the side wall of said housing member 5 is a lateral passage or opening 9 with which is associated a stuffing-box member 10.

The reference character 11 indicates a vertical discharge pipe or tube which is preferably made of glass, and which is provided at its upper end with a laterally projecting arm or extension 12, and at its lower end with a goose-neck or U-shaped portion 13 terminating in an upward extension or arm 14 at the free end of which is an enlarged member or bulb-portion 15 having on its upper surface an upwardly directed sharp spur or piercing point 16. Said enlarged member or bulb-portion 15 is provided in its underside, adjacent to the juncture therewith of said extension or arm 14, with a port or opening 17.

Said discharge pipe or tube 11 is arranged with its upper portion disposed within and at one side of the interior chamber 6 of said

housing member 5, so as to project downwardly through the lower open end of said chamber 6 and into the water reservoir or chamber 2 of the container or jar 1. The 5 laterally projecting arm or extension 12 of said discharge pipe or tube extends outwardly through the passage or opening 9 and through the stuffing-box member 10 connected with said housing member 5, so that 10 the free end of said arm or extension is exteriorly projected from said housing member. Coupled with said exteriorly projected free end of said arm or extension 12 is a suction tube 18, preferably made of a suitable flexible material, such as rubber, and the free end 15 of said suction tube 18 is provided with a suitable mouth-piece 19 made of glass or of any other suitable material. The goose-neck or U-shaped portion 13 off-sets the upward 20 extension or arm 14 so that the latter is disposed in substantial longitudinal vertical alignment with the longitudinal axis of said housing member 5 and its neck-portion 7. Suitably secured within the lower open end 25 of said housing member 5, so as to extend downwardly therefrom into the water reservoir or chamber 2 of the container or jar 1, and so as to enclose the downwardly extending discharge pipe or tube and the extension or arm 14 and associated parts thereof, is a tubular bell-member 20 having an open lower extremity or mouth.

The reference character 21 indicates a guide-ferrule, having at its underside a stopper portion 22 which fits into the upper open end of said neck-portion 7 of the housing member 5, and having at its upper end a laterally projecting annular flange 23, the peripheral surface of which is preferably 40 knurled, and which provides a finger-piece for grasping said guide-ferrule when connecting or disconnecting the same from normal operative relation to the neck-portion 7. Said guide-ferrule 21 is provided with a central vertical or axially aligned opening or guideway 24, in which is slidably disposed for vertical movement the stem 25 of a capsule or cartridge holder. Said capsule or 45 cartridge holder, which is connected with the lower or inner end of said stem 25, comprises a tubular socket-member 26, the walls of which are provided with longitudinal slits 27 extending upwardly from the lower open end of said socket-member, to thus provide 50 more or less yieldable or resilient wall-sections for frictionally engaging and holding a capsule or cartridge 28 which contains the radium emanation to be administered to the user of the device. The upper free end of 55 said stem 25 projects above the guide-ferrule 21, and is preferably provided with a finger piece 29. Formed in the exterior portion of said stem 25 are a series of vertically spaced apart annular grooves, respectively shaped 60 to provide at their upper sides the respective

rectangular stop-shoulders 30, 31 and 32, and at their lower sides with the respective inclined or chamfered shoulders 30', 31' and 32', which incline outwardly from the inner margins of said stop-shoulders to meet the outer surface of said stem. Said stem is also provided with a vertical channel or groove 33 providing a gate in the stop-shoulder 30 leading upwardly to the stop-shoulder 31; and said stem is further provided with a similar vertical channel or groove 34 providing a gate in the stop-shoulder 31 leading upwardly to the stop-shoulder 32. Said respective channels or grooves 33 and 34 are off-set in non-alined relation one to the other. Connected with said neck-portion 7 or otherwise suitably fixed and mounted is a yieldable spring stop-member or detent 35, the free end of which rides against the side of said stem 25.

The capsule or cartridge 28, to be used with the above-described apparatus, is preferably made of glass in the form of a small test-tube. The capsules or cartridges are charged with proper quantities of radium emanation at the distributing laboratory and the open ends are then sealed by a suitable frangible cap or cover 28'. The capsules or cartridges are then sent to the patient possessing the novel administering apparatus. Each capsule or cartridge contains a plurality of doses, that is a sufficient quantity of radium emanation to afford several administrations of a prescribed dosage proportion. In making use of the administering apparatus, the patient first fills the chamber 2 of the main container or jar 1 with water. He then removes the guide-ferrule 21 from the neck-portion 7 and withdraws therewith the capsule or cartridge holder, thereupon inserting into the latter a capsule or cartridge with its sealed end downward, as shown in the drawings. Before inserting the guide-ferrule 21 into operative relation to the neck-portion 7, the stem 25 is drawn upward and outward so that all the stop-shoulders 30, 31 and 32 are exposed. The parts being then assembled in operative connected relations, the patient places the mouth-piece of the suction tube 18 in his mouth, and then presses downwardly the stem 25 until the stop-shoulder 30 is arrested by the detent 35. In thus pressing down the stem 25 the capsule or cartridge socket is lowered so that the sealed end of the capsule or cartridge is carried into engagement with the piercing point 16, which penetrates and breaks the seal 28' and permits the bulb-portion 15 of the discharge pipe or tube to enter and extend part way into the interior of said capsule or cartridge. The patient now sucks upon the mouth-piece 19, thus creating a partial vacuum in the suction tube and the discharge pipe or tube, whereupon a portion of the

radium emanation contained in the capsule or cartridge will be caused to flow by way of the port or opening 17 into the bulb-portion 15 and thence into the discharge pipe or tube 5 and suction tube, and thus to the mouth of the patient for inhalation. As a portion of the radium emanation is thus displaced from the capsule or cartridge, the pressure thereof within the latter is relieved, and water from 10 the chamber 2 will flow into and rise within the capsule or cartridge until it covers the port or opening 17, thus water-sealing the capsule or cartridge and the discharge pipe or tube against any further passage of radium emanation from said capsule or cartridge. When the patient sucks water he is at 15 once advised that the dose of radium emanation has been discharged and administered, and suction on the suction tube is discontinued. Since the stop-shoulder 30 is so positioned that it permits only a partial penetration of the receiving end of the discharge pipe or tube into the capsule or cartridge, and since the rise of water into sealing or 20 closing relation to the port or opening 17 shuts off further discharge of the radium emanation from the capsule or cartridge, it follows that a considerable quantity of said radium emanation is trapped and sealed 25 against escape from the capsule or cartridge, and is thus held for future use. When the patient wishes to take a second dose or inhalation of the radium emanation, the stem 25 is given a partial rotation about its vertical axis until the channel or groove 33 is 30 alined with the detent 35, whereupon the stem and capsule or cartridge holder are lowered another stage until stopped by the engagement of the stop-shoulder 31 with the 35 detent 35, to thereby cause the bulb-portion 15 and its port or opening 17 to rise in the capsule or cartridge above the water level previously established therein so as to break the water-seal and permit the suction and 40 discharge of a second quantity of the radium emanation. Upon the discharge of said second quantity of radium emanation, the water will displace the same and will rise again to sealing relation to the port or opening 17, 45 thus again trapping and sealing off the remaining quantity of radium emanation for future use. A third dose or inhalation may be administered to the patient in the same way, by again rotating the stem 25 to aline 50 the channel or groove 34 with the detent 35, and then pushing down the stem until the stop-shoulder 32 is arrested by the detent 35, whereupon the bulb-portion 15 and its 55 port or opening 17 will fully penetrate the interior of the capsule or cartridge in position to discharge therefrom the radium emanation remaining therein. It will be understood in retracting or raising the stem 25, the 60 detent 35 will easily ride over the inclined or 65 chamfered portions 30', 31' and 32' so that a straight upward pull will raise the capsule or cartridge holder to upwardly drawn initial position. By substituting full or charged capsules or cartridges for those emptied, the apparatus may be repeatedly 70 used to administer doses of radium emanation for inhalation by the patient.

I am aware that some changes may be made in the various arrangements and combinations of the several devices and parts 75 making up my present invention, as well as in the details of the construction of the same, without departing from the scope of the invention as set forth in the foregoing specification and as defined in the appended claims. 80 Hence, I do not limit my invention to the exact arrangements and combinations of the several devices and parts as described in said foregoing specification, nor do I confine myself to the exact details of the construction of said parts as illustrated in the accompanying drawings.

I claim:—

1. In a device of the kind described, a water container, a discharge tube having an exteriorly directed upper end and a lower end disposed within said container, an upwardly directed receiving arm connected with said lower end of said discharge tube, said arm having an intake port adjacent to its free extremity, a vertically movable capsule holder, and means for guiding said capsule holder, downward movement of said capsule holder being adapted to move a capsule supported thereby into operative 95 relation to the receiving arm whereby the latter penetrates the interior of said capsule to permit the content thereof to enter said intake port and be withdrawn through said discharge tube.
2. In a device of the kind described, a water container, a discharge tube having an exteriorly directed upper end and a lower end disposed within said container, an upwardly directed receiving arm connected 100 with said lower end of said discharge tube, said arm having a bulb-like extremity provided with an upwardly directed piercing point, said bulb-like extremity having a receiving port in its side, a vertically movable 105 capsule holder for supporting a sealed capsule, means for guiding said capsule holder whereby downward movement thereof enters said receiving arm into said capsule to permit the content of the latter to be withdrawn 110 through said discharge tube, and a suction tube having a mouth-piece connected with the exterior end of said discharge tube.
3. In a device of the kind described, a water container, a discharge tube having an exteriorly directed upper end and a lower end disposed within said container, an upwardly directed receiving arm connected with said lower end of said discharge tube, said arm 115 having a bulb-like extremity provided with 120

- an upwardly directed piercing point, said bulb-like extremity having a receiving port in its side, a vertically movable capsule holder for supporting a sealed capsule, 5 means for guiding said capsule holder whereby downward movement thereof enters said receiving arm into said capsule to permit the content of the latter to be withdrawn through said discharge tube, a detent means, and means connected with said capsule holder to cooperate with said detent means whereby the downward movement of said capsule is limited to successive stages to enter said receiving arm step by step into 10 said capsule.
4. In a device of the kind described, a water container, a discharge tube having an exteriorly directed upper end and a lower end disposed within said container, an upwardly directed receiving arm connected with said lower end of said discharge tube, said arm having a bulb-like extremity provided with an upwardly directed piercing point, said bulb-like extremity having a receiving port in its side, a vertically movable capsule holder for supporting a sealed capsule, means for guiding said capsule holder whereby downward movement thereof enters said receiving arm into said capsule to permit the content of the latter to be withdrawn through said discharge tube, a detent means, means connected with said capsule holder to cooperate with said detent means whereby the downward movement of said capsule is limited to successive stages to enter said receiving arm step by step into said capsule, and a suction tube having a mouth-piece connected with said exterior end of said discharge tube.
5. In a device of the kind described, a water container having an open upper end, a housing fitted into the open end of and communicating with the interior of said container, a suction actuated discharge tube connected with said housing to extend from the interior thereof downwardly into said container, said discharge tube having its upper end disposed to project exteriorly from said housing, said discharge tube having an upturned lower end portion provided at its extremity with a piercing member and an intake port adjacent said piercing member, a vertically movable capsule holder alined with said upturned lower end portion of said discharge tube, means for guiding said capsule holder, downward movement of said capsule holder being adapted to move a capsule supported thereby into operative relation to said receiving end of said discharge tube whereby the latter penetrates the interior of said capsule and communicates with the content thereof.
6. In a device of the kind described, a water container having an open upper end, 60 a housing fitted into the open end of and communicating with the interior of said container, a suction actuated discharge tube connected with said housing to extend from the interior thereof downwardly into said container, said discharge tube having its upper end disposed to project exteriorly from said housing, said discharge tube having an upturned lower end portion provided at its extremity with a piercing point and an intake port adjacent said piercing point, a tubular bell-member depending from said housing member into said water container and surrounding the interiorly disposed part of said discharge tube and its upturned lower end portion, a vertically movable capsule holder alined with said upturned lower end portion of said discharge tube, means for guiding said capsule holder, downward movement of said capsule holder being adapted to move a capsule supported thereby into operative relation to said receiving end of said discharge tube whereby the latter penetrates the interior of said capsule and communicates with the content thereof.
7. In a device of the kind described, a water container having an open upper end, a housing fitted into the open end of and communicating with the interior of said container, a suction actuated discharge tube connected with said housing to extend from the interior thereof downwardly into said container, said discharge tube having its upper end disposed to project exteriorly from said housing, said discharge tube having an upturned lower end portion provided at its extremity with a piercing point and an intake port adjacent said piercing point, a tubular bell-member depending from said housing member into said water container and surrounding the interiorly disposed part of said discharge tube and its upturned lower end portion, a vertically movable capsule holder alined with said upturned lower end portion of said discharge tube, means for guiding said capsule holder, a detent means, and means connected with said capsule holder to cooperate with said detent means whereby said capsule holder may be moved downwardly only by successive stages to enter the receiving end of said discharge tube step by step into a capsule supported by said capsule holder.
8. In a device of the kind described, a water container having an open upper end, a housing fitted into the open end of and communicating with the interior of said container, a suction actuated discharge tube connected with said housing to extend from the interior thereof downwardly into said container, said discharge tube having its upper end disposed to project exteriorly from said housing, said discharge tube having an upturned lower end portion provided at its extremity with a piercing point and an intake port adjacent said piercing point, a tubular bell-member depending from said housing member into said water container and surrounding the interiorly disposed part of said discharge tube and its upturned lower end portion, a vertically movable capsule holder alined with said upturned lower end portion of said discharge tube, means for guiding said capsule holder, downward movement of said capsule holder being adapted to move a capsule supported thereby into operative relation to said receiving end of said discharge tube whereby the latter penetrates the interior of said capsule and communicates with the content thereof.
9. In a device of the kind described, a water container having an open upper end, a housing fitted into the open end of and communicating with the interior of said container, a suction actuated discharge tube connected with said housing to extend from the interior thereof downwardly into said container, said discharge tube having its upper end disposed to project exteriorly from said housing, said discharge tube having an upturned lower end portion provided at its extremity with a piercing point and an intake port adjacent said piercing point, a tubular bell-member depending from said housing member into said water container and surrounding the interiorly disposed part of said discharge tube and its upturned lower end portion, a vertically movable capsule holder alined with said upturned lower end portion of said discharge tube, means for guiding said capsule holder, downward movement of said capsule holder being adapted to move a capsule supported thereby into operative relation to said receiving end of said discharge tube whereby the latter penetrates the interior of said capsule and communicates with the content thereof.

portion of said discharge tube, means for guiding said capsule holder, a detent means, and means connected with said capsule holder to cooperate with said detent means whereby said capsule holder may be moved downwardly only by successive stages to enter the receiving end of said discharge tube

step by step into a capsule supported by said capsule holder.

In testimony that I claim the invention set forth above I have hereunto set my hand this 4th day of September, 1923.

HARRY B. PALMER.
